UNITED STATES PATENT OFFICE.

LEOPOLD ELIAS, OF KOSTEN, PRUSSIA, GERMANY.

MANUFACTURE OF GLAZED PAPER FOR BAGS, &c.

SPECIFICATION forming part of Letters Patent No. 372,408, dated November 1, 1887.

Application filed August 14, 1886. Serial No. 210,935. (Specimens.)

To all whom it may concern:

Be it known that I, LEOPOLD ELIAS, manufacturer, a subject of the King of Prussia, and a resident of Kosten, in the Kingdom of Prussia, 5 German Empire, have invented a new and useful Improvement in Manufacturing Glazed Papers, of which the following is a specification.

My invention relates to improvements in manufacturing glazed papers—such as are used either in the shape of cornets, bags, card-board boxes, &c.—for packing tea, coffee, cocoa-powder, pudding-meal, flour for children, maize-meal, soup-meal, almond-powder, ver- 15 min-powder, metal colors, snuff, &c., in, or are else utilized in the shape of business-cards, gratulatory-cards, announcements of engagements, marriages, births, or deaths, bills, price-lists, circulars, calendars, cigar-tubes, covers 20 for books, &c.

The object of my improvement is the combination of an outside cover or upper layer composed of a transparent shining paper (cambric or waxed paper) with a cover lying beneath it and composed of a shining leaf of metal, (tin or gold foil, silver or gold tissue-paper,) which may be stretched over an inner cover or leaf of common paper or card-board for the purpose of making a packing material 30 the outside of which is dimly shining. This new paper material consists, therefore, first, of an inner leaf composed of common paper or any other suitable material; secondly, of a brightly-shining leaf of metal, such as tin or 35 gold foil or any other suitable leaf metal; and, thirdly, of a cover or upper layer stretched over the above-named materials and composed of transparent shining paper, such as cambric or waxed paper. Owing to the second layer

being composed of a shining material, the upper layer or cover stretched over it acquires a subdued metallic shine, which, for instance, has the appearance of satin whenever tin-foil or painted silver-paper is used, and makes an extremely agreeable impression on the eye. 40 The combined effect of the transparent shining outer cover or layer, made of cambric or waxed paper, and the shining layer beneath it, made of metal leaf, forms the characteristic peculiarity of this invention. These two covers or 45 layers can be used for themselves and without the above-named inner layer of common paper and without my invention being influenced thereby.

It must further be remarked that, owing 50 to the shining through of the leaf metal or metallic paper of which the second layer is composed, the print on the upper layer has a strongly metallic shine, which makes it all the more conspicuous, so that the combination just 55 described proves very advantageous for business-cards, &c.

What I claim, and desire to secure by Letters Patent of the United States, is—

As a new article of manufacture, an ornamental compound material consisting of an outer layer of translucent shining cambric or waxed paper, a middle layer of foil, and a third or under layer of common paper for preserving the middle layer of foil, substantially 65 70 as described.

In witness whereof I have hereunto set my hand in presence of two witnesses.

LEOPOLD ELIAS.

Witnesses:

A. MÜHLNER,
B. RÖL.
